SELF-UNLOADING CAR.

1,408,334.

Specification of Letters Patent. Patented Feb. 28, 1922.

Application filed December 12, 1913. Serial No. 806,261.

To all whom it may concern:

Be it known that I, KARL BARTH, residing at Essen-on-the-Ruhr, Germany, a subject of the Emperor of Germany, have invented a certain new and useful Improvement 5 in Self-Unloading Cars, of which the following is a specification.

This invention relates to self-unloading vessels described in my copending application Serial No. 796272 and one object is to insure the complete emptying of the vessel for the loading material.

In the accompanying drawing is illustrated one embodiment of the invention 15 representing a self-unloading car, and

Fig. 1 shows in cross section a car in loading position and

Fig. 2, a similar view to Fig. 1 with the car in discharge position.

20 In the main, the present self-unloading car is of the same construction as the one shown in the above named copending application, excepting for the differences enumerated below. As far as possible, the same characters have been used for similar parts 25 of this as for the car of the copending application.

The two end walls A¹ are rigidly secured on the bottom frame A of the car, and 30 these walls are reinforced at their corners by two rods a² and a³ parallel to the longitudinal axis of the car. The bottom B of the self-unloading car is, by means of a shaft b¹, revolvably mounted in bearings in 35 the end walls A¹, and this shaft is situated on the side of the car nearest to the rod a². The side wall C on this side of the car has a hinged connection with the bottom B and is at its upper end provided with guides c¹, 40 which are guided on suitable rollers a⁴ mounted on the rod a². The guides c¹ are bent at their upper ends, into hooks c², with which they engage the rollers a⁴ in the loading position of the car, see Fig. 1, so that 45 the bottom B is secured against turning in the direction of the arrow y. The opposite side wall C³ is hinged to the rod a³ and is provided with hooks c⁴ at its lower end, which hooks grip under the bottom B and 50 hold it in the loading position as illustrated in Fig. 1. In discharging position shown in Fig. 2, the bottom B rests on a beam a⁵ secured on a bottom frame A of the car. A push rod D, hinged to the side wall C³, is 55 intended both to hold the latter in closed

position or to swing it outward to open by pushing on the rod D, when the hooks c⁴ will release the bottom B.

The new feature of the present invention resides therein that the position of the 60 shaft b¹ has been so selected that the bottom B and the side wall C are not able to swing automatically from the open position, that is the discharge position in Fig. 2, into the closed position, that is the loading position 65

in Fig. 1, as is the case with the car represented in the copending application; but that they are instead only brought by hand into the closed position Fig. 1 by the use of a special drive. For this purpose, a 70 longitudinal shaft E, provided with several parallel crank arms E¹, is mounted in bearings on the under frame of the car, and may be revolved by means of a hand lever E² secured to one of its ends. Each crank 75 arm E¹ is connected by means of a link F, with a tension rod G, hinged to the side wall C. The link F and the tension rod G are each provided with an abutment f¹ and g¹. These two abutments come into contact when the two members F and G are approximately in alignment so that the obtuse angle of slightly less than 180° formed by the two members, is turned 80 towards the central plane of the car; compare the position in dot and dash lines of the members in Fig. 2 and of the member F in Fig. 1. In order to secure the hand lever E² in its position of rest, in the drawing indicated by dotted lines, a pawl H has been 85 provided on one of the end walls A¹. As indicated by full lines in the drawing the crank arms E¹ are directed upwards, with the hand lever E² in the said position, and the tension rods G are both in the closed position 90 as well as in the open position of the bottom B, approximately parallel to arms E¹. In the former case, the tension rods G forms approximately a right angle with the links F, and in the latter case an obtuse angle, which is smaller than the angle which the abutments f¹ and g¹ form when impinging with each other.

During transportation, the hand lever E² is secured to the end wall A¹ by means of 105 the pawl H. If the car is to be unloaded, the side wall C³ has to be swung outwards, by means of the push rod D, of which only the portion connected to the side wall C³ has been shown for the sake of clearness; 110

whereupon the bottom B, actuated by the weight of the load, swings into the open position, Fig. 2. The hand lever E² retains during this time its position of rest, and 5 only the members F and G turn from the position shown by full drawn lines in Fig. 1 into the similarly indicated position in Fig. 2.

Whilst in accordance with the embodiment shown in the copending application, 10 the bottom B and the side wall C hinged thereto, thereupon automatically returns to the position shown in Fig. 1, they remain, in consequence of the preponderance, which 15 the bottom has on its side away from the side wall C, in the position shown in Fig. 2 in accordance with the present embodiment. If no preponderance existed on this side, the bottom and the side wall C might return to the closed position, Fig. 1, before the car 20 had been completely unloaded, in case the material during its precipitation were accidentally distributed in such a mass, that a pressure against the side wall C and the 25 portion of the bottom B situated between this side wall and the shaft b¹, were approximately the same as, or in excess of the pressure against the rest of the bottom. This disadvantage may be prevented by a 30 suitable selection of the preponderance.

When, after unloading, the bottom B is to be swung back into closed position, the hand lever E² is relieved and then turned in the direction of arrow x, from the dotted position in Fig. 2. The angle formed between the members F and G will then first change until the abutments f¹ and g¹ of the links F and the tension rods G abut against each other, as will occur with the parts E² E¹ F 40 and G in the position indicated by dot and dash lines in Fig. 2. In subsequent turning of the hand lever E², the members F and G constitute a rigid body, so that the side wall C is drawn downwards and the bottom E 45 simultaneously approaches the closed position. When the bottom B has reached that position in which the hand lever E² is situated as indicated by dot and dash lines in Fig. 1, the side wall C³ will then be swung 50 inwards by means of the push rod D until the claws c⁴ grip underneath the bottom B and retain the latter in place. Finally the hand lever E² is returned to its initial position and secured in that position by its pawl 55 H. The position of the bottom and the side wall C are not influenced by this movement of the hand lever as the members F and G are free to bend inwards. On account of the lever transmission, only a small expenditure 60 of power is necessary for transferring the bottom B and the side wall C from the open position, Fig. 2, into the closed position Fig. 1.

The arrangement of the drive E² E E¹ F 65 G provides still another advantage particu-

larly with regard to loading material, which cakes together namely that any material remaining on the bottom or the side wall C can be easily and conveniently removed. For this purpose it will be enough to let 70 the bottom B drop, repeatedly if necessary, after it has been raised a certain amount from its position in Fig. 2 by means of the drive E² E E¹ F G. In consequence of the shaking, caused by the striking of the bottom of the beam a⁵, the remnants will then 75 detach themselves.

I claim:

1. A self-unloading vessel comprising a frame, a receptacle of rectangular cross-section when in loading position, said receptacle having two end walls rigidly mounted on said frame, a bottom forming an unloading member of the vessel and adapted to swing about a longitudinal axis of the receptacle situated between the central longitudinal plane and one of the side walls, said side wall forming another unloading member of the vessel, hinged connection between this side wall and said bottom, an operating member and connection between said unloading members and said operating member for returning said unloading members into closed position after unloading. 80

2. A self-unloading vessel comprising a frame, a receptacle of rectangular cross-section when in loading position, said receptacle having two end walls rigidly mounted on said frame, a bottom, forming an unloading member of the vessel and adapted to swing about a longitudinal axis of the receptacle, situated between the central longitudinal plane and one of the side walls, said side wall forming another unloading member of the vessel, hinged connection between this side wall and said bottom, an operating member and connection between said unloading members and said operating member for returning said unloading members into closed position after unloading, 85 said operating member being independently turnable in and out of closing position while said unloading members are in closed position, but actuating said unloading members for closing them when in open position. 90

3. A self-unloading vessel comprising a frame, a receptacle of rectangular cross-section when in loading position, said receptacle having two end walls rigidly mounted on said frame, a bottom, forming an unloading member of the vessel and adapted to swing about a longitudinal axis of the receptacle, situated between the central longitudinal plane and one of the side walls, said side wall forming another unloading member of the vessel, hinged connection between this side wall and said bottom, an operating member and connection between said unloading members and said operating member for returning said unloading members into closed position. 95

sition after unloading, said connection comprising a tension rod hinged to a part positively connected to one of said unloading members, a rock shaft carrying said operating member, a crank arm on said rock shaft and a link pivoted to said crank arm and said tension rod.

4. A self-unloading vessel comprising a frame, a receptacle of rectangular cross-section when in loading position, said receptacle having two end walls rigidly mounted on said frame, a bottom, forming an unloading member of the vessel and adapted to swing about a longitudinal axis of the receptacle, situated between the central longitudinal plane and one of the side walls, said side wall forming another unloading member of the vessel, hinged connection between this side wall and said bottom, an operating member and connection between said unloading members and said operating member for returning said unloading members into closed position after unloading, said connection comprising a tension rod hinged to a part positively connected to one of said unloading members, a rock shaft carrying said operating member, a crank arm on said rock shaft and a link pivoted to said crank arm

and said tension rod, an abutment on said tension rod and a corresponding abutment on said link cooperating with said first abutment for producing a stiff joint between said link and arm, with said unloading members in open position and said operating member turning in the direction to close them. 35

5. A car having fixed end walls, a pivotally mounted bottom member, the pivotal axis of which is intermediate the sides of said bottom member, a side member pivotally mounted between the said end walls 40 and adapted to open outwardly from the car and to close inwardly and downwardly on the outer side of the bottom member, when the latter is in closed position, a vertically movable wall pivotally connected to the bottom member at the side opposite the said side member, and means to raise and lower the said wall and thereby actuate the bottom member and the side member.

The foregoing specification signed at Bar- 50 men, Germany, this 18th day of November, 1913.

KARL BARTH. [L. S.]
